GAS COMPRESSOR

Howard H. Carpenter, Pasadena, Calif.

Application February 1, 1933, Serial No. 654,575

14 Claims. (Cl. 230—108)

My invention relates to centrifugal gas compressors using a liquid as a compression medium; and the principal or general objects of my invention are first, to provide a compressor having a higher efficiency than now attained; second, to effect a substantially complete separation of the liquid compression medium from the gas being compressed; third, the creation of higher pressures than have been formerly obtained with this type of compressor. The invention has other more specific objects which will be obvious to those skilled in the art, in the light of the following description of a preferred embodiment of the invention.

15 In the accompanying drawing forming a part of this specification,—

Fig. 1 is a sectional elevation;

Fig. 2 is a section on the line 2—2 of Fig. 1; and

Fig. 3 shows an enlarged vertical section of one 20 of the high pressure gas units.

1 indicates the shell or casing member enclosing the rotor 2 adapted to be rotated by the electric motor 3 or other power means through the hollow shaft 4. The upper end of the hollow shaft 4 passes through the stuffing box 5 permitting the compressed gases to be discharged through the outlet pipe 6. As shown, the casing 1 holds a body of liquid 7 used as the medium of compression, although a pipe or separate tank 30 could be employed as a source of supply if desired. In the casing 1 there is the gas inlet 8, and the rotor has a tapered liquid inlet 9 with longitudinal vanes 10 depending from the rotor into the liquid 7. 11 is a low pressure gas conduit and 12 the high pressure conduit for the gas, both of said conduits being annular and preferably formed by walls in the rotor. 13 is a low pressure gas inlet for conduit 11, and 14 designates the high pressure gas discharge members 40 which take gas from the high pressure conduit 12 and discharge it through the liquid, as will be described.

Liquid traps are shown at 15 for the low pressure side and at 16 for the high pressure side. 45 17 is the central chamber into which the liquid, at low pressure, is initially drawn. When the rotor 2 is under rotation, the position of the liquid will be as shown at 18, with the inlet gas ducts shown at 19, on the low pressure side; and on the high pressure side, 21 indicates the position of the compression liquid, and 24 the liquid inlet to one of the gas discharge members 14, shown in Fig. 3. The low pressure conduit 11 and the high pressure conduit 22 leading to the high pressure conduit 12 form part of the rotor 2. The liquid compres-

sion medium enters inlet 28, passes through intermediary conduits 29 and 30, and escapes from the rotor at the outlet 31. Stationary hydraulic turbine blades are secured to the casing 1 as shown at 32, and co-operating blades mounted on the rotor 2 are shown at 33, the arrangement being such that the liquid, under pressure as it leaves outlet 31, is diverted by the stationary blades 32 and expends most of its kinetic energy against the rotor blades 33.

10 In operation, the rotor 2 on being rotated by the electric motor 3 (or any other power means such as belt, gears, etc.) draws the liquid 7 up from the bottom of the casing through the rotor inlet 9 and the conduit 29 and by the action of 15 centrifugal force the liquid is thrown around the outer rim of the chamber 17. The liquid passes into the chamber 20 through the conduit 30, the conduit 30 being submerged below the surface of the liquid in the chamber 20 to form the gas 20 seal 15.

After the liquid flows around the outer circumference of the chamber 20 it is discharged through the outlet 31 back into the container 1 for reuse. The liquid serves as the only compression 25 medium, and is continually circulated through the compression member. If desired, the liquid may flow to waste and new liquid may be supplied constantly from an outside source of supply.

The gas to be compressed passes through the inlet 8 to the conduit 11. The liquid under centrifugal force is on the outer rim of chamber 17, and as it flows towards the conduit 30 draws from the submerged tubes 19 gas from the conduit 11 into the body of the liquid in the form of bubbles 35 (illustrated in Fig. 2), which rise to the surface and occupy the space in the chamber 17 not filled by the liquid.

From chamber 17 the gas, now under compression, passes through conduit 22 to the circular 40 conduit 12 to undergo a second stage of compression. From conduit 12, the discharge members 14 receive their supply of gas through inlet tubes 26 (Fig. 3) and discharge into the body of the liquid in chamber 20 through the outlets 27.

45 Greater capacity and efficiency are attained especially in the higher pressures by passing a jet of liquid through the inlet tube as shown in enlarged section in Fig. 3. The jet of liquid issuing from the nozzle 25 is fed by the flowing liquid filling the funnel 24, or the nozzle 25 may be fed from any other convenient source of liquid. Such a liquid gas inlet feed, or a plain tube, may be used in either low or high pressure or single compression units. Baffle plates as shown at 35 may be 50 55

used to assist the bubbles of gas to be deflected to the surface of the compression liquid in chamber 20. A gas compression seal is formed at 16 to prevent the compressed gas in chamber 20 from escaping with the liquid at outlet 31. The compressed gas in chamber 20 is conveyed through a conduit 34 extending radially inwardly to the rotating outlet 4 and thence to the stationary outlet pipe 6.

10 The centrifugal action on the gas as compressed in the high and low pressure chambers causes a substantially complete separation of moisture and the delivery of a substantially dry gas to the outlet, a result difficult to obtain in the present form 15 of hydraulic gas compressors.

This compressor makes it possible to compress a relatively large volume of gas in proportion to the amount of liquid circulated through the rotor, and therefore a considerable saving in power is effected.

20 A further saving of power is attained by utilizing a greater part of the kinetic energy of the liquid being discharged through the outlet nozzle 31 impinging on the stationary turbine blades 32 and deflected onto the moving turbine blades 33 forming a part of the rotor member 2.

It is obvious that if conduit 4 were connected to the circular conduit 11 and the chamber 20 were opened to the interior of the enclosing casing 1, the gas inlets and outlets would then be reversed and the apparatus would be operative as 30 a compressor. In practice I have found this arrangement to be most desirable for low pressure work. Also, if desired, a single stage of compression, or three or more stages of compression, may be employed. The two stages shown are ordinarily adequate.

It is to be understood that the exact construction 40 of the compressor is not important and the invention may be embodied in various other forms, and that many changes might be made in the compressor as shown without departing from the spirit of the invention.

Having thus described my invention, what I 45 claim as new and desire to secure by Letters Patent is:

1. A compressor comprising, in combination, a casing; a rotor within the casing spaced above the bottom thereof; a supply of liquid in the bottom of the casing; a liquid inlet extending downwardly from the center of the rotor to a point below the liquid level; the rotor having a chamber formed therein to which the liquid is conducted by said inlet; a gas intake in the casing; 50 a gas conduit in communication with said intake and surrounding said chamber; tubes opening into said chamber and gas conduit and so arranged that flow of the liquid draws gas from the gas conduit through said tubes into said chamber; means to conduct the compressed gas away; means to return the liquid in the chamber to the bottom of the casing; and power means to rotate the rotor.

2. A compressor comprising, in combination, a casing; a rotor within the casing spaced above the bottom thereof; a supply of liquid in the bottom of the casing; a liquid inlet extending downwardly from the center of the rotor to a point below the liquid level; the rotor having a chamber formed therein to which the liquid is conducted by said inlet; a gas intake in the casing; a gas conduit in communication with said intake and surrounding said chamber; tubes opening into said chamber and gas conduit and so arranged 70 that flow of the liquid draws gas from the gas

conduit through said tubes into said chamber; a second chamber formed on the rotor outside the gas conduit; means conducting the liquid from the first to the second chamber; a second gas conduit formed on the rotor outside the second chamber; means to conduct gas from the second gas conduit into the second chamber; means to conduct the compressed gas away; means communicating with the second chamber to return the liquid to the bottom of the casing; and power 10 means to rotate the rotor.

3. A compressor comprising, in combination, a casing; a rotor within the casing; a supply of liquid; means to hold the supply of liquid; a liquid inlet extending downwardly from the center of the rotor to a point below the liquid level; the rotor having a chamber formed therein to which the liquid is conducted by said inlet; a gas intake in the casing; a gas conduit in communication with said intake and surrounding said chamber; tubes opening into said chamber and gas conduit and so arranged that flow of the liquid draws gas from the gas conduit through said tubes into said chamber; a second chamber formed on the rotor outside the gas conduit; means conducting the liquid from the first to the second chamber; a second gas conduit formed on the rotor outside the second chamber; means to conduct gas from the second gas conduit into the second chamber; means to conduct the compressed gas away; means communicating with the second chamber to convey the liquid to the outer rim of the rotor; turbine blades formed on said outer rim; stationary turbine blades formed on the casing adjacent but inside the rotor rim; and power 20 means to rotate the rotor.

4. A compressor comprising, in combination, a casing; a rotor within the casing; a supply of liquid; a liquid inlet extending downwardly from the center of the rotor to a point below the liquid level; the rotor having a chamber formed therein to which the liquid is conducted by said inlet; a gas intake in the casing; a gas conduit in communication with said intake and surrounding said chamber; tubes opening into said chamber and gas conduit and so arranged that flow of the liquid draws gas from the gas conduit through said tubes into said chamber; a second chamber formed on the rotor outside the gas conduit; means conducting the liquid from the first to the second chamber; a trap positioned to prevent the flow of compressed gas into the second liquid chamber; a gas compression seal to prevent escape of compressed gas; a second gas conduit formed on the rotor outside the second chamber; means to conduct gas from the second gas conduit into the second chamber; means to conduct the compressed gas away; means communicating with the second chamber to return the liquid to the means for holding the same; and power means to rotate the rotor.

5. A compressor comprising, in combination, a casing; a rotor within the casing spaced above the bottom thereof; a supply of liquid in the bottom of the casing; a liquid inlet extending downwardly from the center of the rotor to a point below the liquid level; the rotor having a chamber formed therein to which the liquid is conducted by said inlet; a gas intake in the casing; a gas conduit in communication with said intake and surrounding said chamber; tubes opening into said chamber and gas conduit and so arranged that flow of the liquid draws gas from the gas conduit through said tubes into said

- chamber; a second chamber formed on the rotor outside the gas conduit; means conducting the liquid from the first to the second chamber; a second gas conduit formed on the rotor outside the second chamber; means to conduct gas from the second gas conduit into the second chamber; baffles in the second chamber fixed and shaped so as to assist the bubbles of gas to be deflected to the surface of the liquid in the second chamber; means to conduct the compressed gas away; means communicating with the second chamber to return the liquid to the bottom of the casing; and power means to rotate the rotor.
6. A compressor comprising, in combination, a casing; a rotor within the casing; a supply of liquid; a liquid inlet connecting the center of the rotor with the supply of liquid; the rotor having a liquid chamber therein; a gas intake in the casing; a gas conduit in the rotor in communication with said intake and surrounding the liquid chamber; conduits opening at their opposite ends into said liquid chamber and gas conduit and so arranged that flow of the liquid draws gas from the gas conduit through said conduits into said liquid chamber; means to conduct away the compressed gas; and power means to rotate the rotor.
7. A compressor comprising, in combination, a rotor; power means to rotate the rotor; a casing enclosing the rotor; a liquid chamber located centrally of the rotor; a liquid inlet; a gas inlet; an annular gas conduit surrounding said chamber and connected to the gas inlet; means to draw gas from said annular conduit into the chamber; a gas conduit open to the central part of said chamber and extending outwardly radially of the rotor; an annular chamber surrounding said annular gas conduit; an annular conduit surrounding said annular chamber and communicating with said radial gas conduit; means to draw gas from the last named annular conduit into said annular chamber; means at the periphery of the rotor to discharge the liquid from within the annular chamber; a gas conduit extending radially inwardly from said annular chamber to the center of the rotor; and means connected to the last named gas conduit to conduct away the compressed gas.
8. A compressor comprising, in combination, a rotor; an electric motor having its shaft co-axial with and secured to the rotor; said shaft being hollow; a stuffing-box at the outer end of said shaft; a compressed gas discharge pipe connected with the stuffing-box; a gas inlet in the rotor; a liquid inlet also in the rotor; a source of liquid supply; means on the rotor to draw the gas in the form of small bubbles into the liquid; means to collect the gas as it separates from the liquid; a gas seal; means to discharge the liquid; and a conduit leading from the gas-collecting means to the inner end of said hollow shaft.
9. A compressor comprising, in combination, a rotor; power means to drive the rotor; a casing enclosing the rotor; a gas inlet in the casing; a gas conduit formed on the rotor and communicating with the gas inlet; a liquid inlet on the rotor; a chamber located centrally of the rotor and receiving liquid from said inlet; means in said chamber to draw the gas from said gas conduit in the form of small bubbles into the liquid in the chamber; a conduit conducting the liquid from said chamber into a second chamber which is outside of the first; a conduit conducting the gas separating from the liquid in the first-named chamber; an annular gas conduit outside of the second chamber; and to which the gas is led; a discharge outlet for the liquid in the second chamber; a stationary set of turbine blades secured to the casing and located just beyond the path of revolution of the extremity of the discharge outlet; and a complementary set of turbine blades fixed to the periphery of the rotor and located just outside of the stationary set of turbine blades, the arrangement being such that much of the kinetic energy of the liquid issuing from the discharge outlet is utilized to turn the rotor.
10. A compressor comprising, in combination, a casing; a rotor within the casing; power means to rotate the rotor; a supply of liquid; a liquid inlet connecting the rotor with the supply of liquid; the rotor having a liquid chamber therein; a gas intake in the casing; a gas conduit in the rotor in communication with said gas intake; conduits opening at their opposite ends into said gas conduit and liquid chamber and so arranged that flow of the liquid draws gas through said conduits into said liquid chamber; means to conduct away the compressed gas; means to discharge the liquid from the liquid chamber in a generally radial direction, outwardly from said liquid chamber; and turbine blades on the casing and rotor adapted to utilize part of the kinetic energy of the discharged liquid to assist in rotation of the rotor.
11. A compressor comprising, in combination, a casing; a rotor within the casing; said rotor having a liquid chamber therein; a gas intake in the casing; a gas conduit in the rotor in communication with said gas intake; discharge members communicating with the gas conduit and with the liquid chamber and located in the liquid chamber; said discharge members each being provided with a restricted nozzle on the interior which discharges liquid into an outlet tube of larger size, said outlet tube communicating with the gas conduit and discharging directly into the liquid chamber; and means to conduct away the compressed gas separating from the liquid in the liquid chamber.
12. A compressor comprising, in combination, a casing; a rotor within the casing; said rotor having a liquid chamber therein; a gas intake in the casing; a gas conduit in the rotor in communication with said gas intake; discharge members communicating with the gas conduit and with the liquid chamber and located in the liquid chamber; said discharge members each being provided with a restricted nozzle on the interior which discharges liquid into an outlet tube of larger size, said outlet tube communicating with the gas conduit and discharging directly into the liquid chamber; baffles in the liquid chamber adjacent said outlet tubes to assist the gas bubbles to be deflected to the surface of the liquid in the liquid chamber; and means to conduct away the compressed gas separating from the liquid in the liquid chamber.
13. A compressor comprising, in combination, a casing; a rotor within the casing; power means to rotate the rotor; a supply of liquid; a liquid inlet connecting the rotor with the supply of liquid; the rotor having a liquid chamber therein; a gas intake in the casing; an annular gas conduit in the rotor in communication with said gas intake and surrounding the liquid chamber; a plurality of tubes of relatively small diameter opening at their outer ends into said annular gas conduit and extending into the liquid chamber and so arranged that the flow of the liquid

through said chamber draws gas through said tubes into said liquid chamber; a conduit for compressed gas leading from the central part of said liquid chamber to the outer part of the rotor; an annular gas conduit at the outer part of the rotor; a second liquid chamber located between the outer gas conduit and the gas conduit first mentioned; a conduit conducting liquid from the inner liquid chamber to the outer liquid chamber and providing a trap to prevent the flow of compressed gas into the second liquid chamber; means to discharge the liquid from the second or outermost liquid chamber; a gas compression seal in the outermost liquid chamber to prevent escape of compressed gas therefrom; discharge members communicating with the outermost gas conduit and the second liquid chamber and located in said chamber; said discharge members each being provided with a restricted nozzle on the interior which discharges liquid into an outlet tube of larger size, said outlet tube communicating with the gas conduit and discharging directly into the liquid chamber; and baffles in the outermost liquid chamber adjacent said outlet tube to assist the gas bubbles to be deflected to the surface of the liquid in the second liquid chamber.

14. A compressor comprising, in combination, a casing; a rotor within the casing; power means to rotate the rotor; a supply of liquid; a liquid inlet connecting the rotor with the supply of liquid; the rotor having a liquid chamber therein; a gas intake in the casing; an annular gas conduit in the rotor in communication with said gas intake and surrounding the liquid chamber; a plurality of tubes of relatively small diameter opening at their outer ends into said annular gas conduit and extending into the liquid chamber

and so arranged that the flow of the liquid through said chamber draws gas through said tubes into said liquid chamber; a conduit for compressed gas leading from the central part of said liquid chamber to the outer part of the rotor; an annular gas conduit at the outer part of the rotor; a second liquid chamber located between the outer gas conduit and the gas conduit first mentioned; a conduit conducting liquid from the inner liquid chamber to the outer liquid chamber and providing a trap to prevent the flow of compressed gas into the second liquid chamber; means to discharge the liquid from the second or outermost liquid chamber; a gas compression seal in the outermost liquid chamber to prevent escape of compressed gas therefrom; discharge members communicating with the outermost gas conduit and the second liquid chamber and located in said chamber; said discharge members each being provided with a restricted nozzle on the interior which discharges liquid into an outlet tube of larger size, said outlet tube communicating with the gas conduit and discharging directly into the liquid chamber; baffles in the outermost liquid chamber adjacent said outlet tube to assist the gas bubbles to be deflected to the surface of the liquid in the second liquid chamber; a stationary set of turbine blades secured to the casing and located just beyond the periphery of the rotor; and a complementary set of turbine blades fixed to the periphery of the rotor and located just outside the stationary set of turbine blades, the arrangement being such that much of the kinetic energy of the liquid issuing from the discharge outlet is utilized to turn the rotor.

HOWARD H. CARPENTER.
